UNITED STATES PATENT OFFICE.

PETER F. AUGENBRAUN, OF STAMFORD, CONNECTICUT, ASSIGNOR TO THE YALE & TOWNE MANUFACTURING COMPANY, OF STAMFORD, CONNECTICUT.

AUTOMOBILE DOOR LOCK.

Application filed June 30, 1920. Serial No. 393,044.

To all whom it may concern:

Be it known that I, PETER F. AUGENBRAUN, a citizen of the United States, and a resident of Stamford, in the county of 5 Fairfield and State of Connecticut, have invented certain new and useful Improvements in Automobile Door Locks; and I do hereby declare the following to be a full, clear, and exact description of the invention, such as will enable others skilled in 10 the art to which it appertains to make and use the same.

My invention relates to an improvement in locks for automobile doors, the object being to provide a lock in which deadlocking means for the latch bolt may be controlled and operated by a key lock at the outside of the door by a thumb turn or knob at the inner side, thereby giving access to the car 20 at all times through either door equipped with the lock.

With this end in view my invention consists in a lock having a latch bolt, means for retracting the bolt, a means for deadlocking the bolt, a thumb turn or knob for actuating said dead-locking means from the inner side of the door and a key mechanism for actuating the said dead locking means from the outer side of the door. It further 30 consists in the parts and combination of parts as will be more fully explained and pointed out in the claims.

In the accompanying drawings, Figure 1 is a view in elevation of a section of a door 35 from the outer side thereof showing the key lock; Figure 2 is a similar view from the inner side; Figure 3 is a view in elevation of the lock mechanism removed from the door and showing the key mechanism in its proper relative position; Figure 4 is a view 40 in section on the line A A of Figure 3; Figure 5 is a view in section on the line B B of Figure 3; Figure 6 is a view of the deadlocking slide and thumb knob for actuating the same; Figure 7 is a view in rear section of the cover plate for the deadlocking slide and Figure 8 is a view of the tumbler lock and the bar for connecting the plug of the latter with the deadlocking 50 slide.

9 represents an automobile door recessed on its inner face to receive the lock, the casing 8 of which is in the form of an angle plate, and is secured to the door by screws in the ordinary and well known manner.

Secured to the inner face of the casing 8 is the L-shaped plate 10 which is provided with screw holes for the passage of the screws 11 which secure it to the casing 8, spacing lugs being struck up from the plate around 60 the screw holes therein for holding the plate away from the casing sufficiently to receive the handle lever 12, hub 13 of the outside handle and the projections 14 and 15 from the latch bolt 16.

This latch bolt is mounted to slide against the inner face of the casing 8, and is supported at its rear end between the guide lugs 17 and by its head 16 resting in a slot in the end flange of the casing. The projection 14 on bolt 16 is engaged by the roll back 18 on the outside handle hub 13 for retracting the bolt from the outer side of the door, and the projection 15 is engaged by the handle lever 12 for retracting the 75 bolt from the inside of the car, when the bolt is not deadlocked.

The bolt 16 is recessed on its inner face to permit the handle 12 to pass up in front of same as shown in Figure 3, and this handle is pivoted at 19 to the casing 8 and is normally held in its forward position and in contact with the screw 11 by the spring 20, and the projection 15 on the bolt 16 is held against the opposite edge of the lever by the spring 21 bearing against the rear face of the projection 14 on the bolt, the said spring operating to normally and yieldingly hold the latch bolt in its projected or locking position as shown in Figure 3. When 90 so projected and not deadlocked as will be hereinafter described, this bolt may be retracted from the inside of the car by pulling back on the lever 12 or from the outside by turning the handle connected with the hub 13 carrying the roll back 18.

22 is the dead locking slide located below the bolt and held in place by the cover plate 23 secured to the rear face of casing 8. The slide is mounted to move vertically or toward and away from the bolt 16, and when in its dead locking position its upper end is at the rear of the shoulder 24 on the head 16^a of the bolt and in the path of movement of said head as shown in dotted lines in Figure 3, thus locking the bolt in its projected position.

Mounted in the casing and accessible from the inside of the car is the thumb turn or knob 25 the stem of which is provided

with a wrist pin 26 resting in an elongated slot 27 in the dead locking slide 22. This thumb knob and its stem are prevented from accidental turning movement by the spring 5 washer 23 interposed between the casing 3 and the knob 25, but is free to be turned by the fingers, and when turned shifts the dead locking slide either to its dead-locking position or to a position below the head 16⁰ of the bolt. When it is in its dead locking position, it is in the path of movement of the head of the bolt and absolutely prevents the retraction of the bolt and consequently prevents access to the car through such 15 locked door. The wrist pin 26 actuated by knob 25, and the slot 27 in the deadlocking slide, are so located that when the slide is in its dead locking position the wrist pin may be moved by a pressure exerted directly 20 against the slide, hence when the slide has been shifted to deadlocking position by the thumb knob, it can be shifted to its reverse position by the key mechanism operable from the outside of the door.

25 This key mechanism comprises a cylinder lock 28 of the pin tumbler type, located within a recess in the outer surface of the door and secured thereto by a single screw 29 passing through the door from the inner 30 side and engaging a threaded hole in the rear end of the cylinder of the lock 28. This screw is eccentric to the axis of the cylinder which will prevent the latter from turning in its recessed seat, and any tendency to turn is also prevented by the projecting lug or "dutchman" 28^a driven into the side of the cylinder and which is let into the wood or metal door by the act of driving the cylinder home. The plug of the cylinder 40 carries at its rear or inner end a connecting bar 31 having a loose connection therewith as shown in Figure 8, and the end of this connecting bar is made angular in cross section and tapered to enter the correspondingly shaped opening in the deadlocking hub 32. This hub is mounted to rotate 45 in deadlocking slide cover plate 23 in line with the connecting bar 31, so that when the lock casing and the parts carried thereon are applied and attached to the inner 50 surface of the door, the end of connecting bar 31 will enter the opening in the hub, and connect the latter with the key actuating mechanism.

55 The hub 32 is provided with a laterally projecting finger 33 adapted to engage the shoulders 34 and 35 on the check plate 36 riveted to the dead locking slide 22, so that when hub 32 is turned in one direction, the finger 33 thereon will engage the shoulder 34 and move the slide 22 downwardly thus releasing the bolt 16, and when turned in the opposite direction will engage the shoulder 35 and lift the slide to its deadlocking 60 position. After the slide has been lifted,

the finger 33 clears or passes the shoulder 35 and rests in a position out of the path of the shoulders 34 and 35, thus leaving the slide free to be moved in the opposite direction or to its unlocking position by the thumb knob. If therefore a bolt be deadlocked by the key from the outer side of a door, and access to the car be had through the door at the other side, the slide deadlocking the bolt of the locked door may be 75 retracted by the thumb knob at the inner side, thus freeing the bolt. Again, if the bolts of both doors be free, one door can be deadlocked by the thumb turn at the inner side of the door and the other door by the 80 key from the outer side and either bolt thus deadlocked can be released by the proper key.

It is evident that changes may be made in the details, hence I would have it understood that I do not confine my invention to the details shown and above described.

Having fully described my invention what I claim as new and desire to secure by Letters-Patent, is:—

1. In a lock for automobile doors, the combination of a latch bolt, outside and inside means for retracting the bolt, a slide adapted to be moved into the path of the bolt and engage and deadlock the same, means at the inner side of the door for actuating the slide to deadlock or release the bolt, a key lock operable from the outer side of the door and having a rotary member the said key lock being independent of the bolt actuating means, a bar connected with the rotary member of the key lock and means actuated by the bar for moving the deadlocking slide to its two positions, the said slide actuating means being constructed to be moved out of engagement with the slide after the latter has been moved to dead-locking position by the key so that said slide will be left free to be moved out of engagement with the bolt by the slide operating means at the inner side of the door.

2. In a lock for automobile doors, the combination of a bolt, inside and outside means for retracting the same, a bolt deadlocking slide independent of either of said bolt retracting means, an inside knob for moving the slide to its two positions, the said slide having an elongated slot to receive a projection on the stem of the inside knob, whereby the said knob will move with the slide when the latter is actuated by the key lock, and a key lock independent of the bolt retracting means, for moving the deadlocking slide to its two positions, the said key lock actuating means being normally out of contact with the slide when the latter is in its deadlocking position so as to permit the latter to be freely moved by the inside knob.

3. In a lock for automobile doors, the combination of a latch bolt, outside and inside

means for retracting the same, a vertically movable slide independent of said bolt for deadlocking the bolt, means at the inner side of the door for actuating the slide to deadlock or release the bolt, a key lock operable from the outer side of the door and having a rotary member, a bar connected with said rotary member and means on said bar for actuating the deadlocking slide the said means being normally out of engagement with the latter when the slide is in deadlocking position.

4. In a lock for automobile doors, the combination of a latch bolt, means for actuating the same, deadlocking means for the bolt, a

thumb knob at the inner side of the door for shifting the deadlocking means, a pin tumbler lock secured to the door by a screw bolt passing from the inner side of the latter, a bar carried by the plug of said pin 20 tumbler lock and having disengageable connection with the deadlocking means.

In testimony whereof, I have signed this specification in the presence of two subscribing witnesses.

PETER F. AUGENBRAUN.
